ANTISKID DEVICE FOR SHOES OR THE LIKE

William A. Walthers, Dalton, Wis.

Application March 9, 1937, Serial No. 129,945

7 Claims. (Cl. 36—7.6)

This invention relates to improvements in anti-skid devices and more particularly to a novel attachment to be worn over a shoe or rubber to prevent slipping and to protect the toe or shoe or rubber.

The primary purpose of the invention is to provide a flexible anti-skid device for shoes or rubbers which may be inexpensively manufactured; readily attached or detached; and which will provide comfort in walking.

With the foregoing object outlined and with other objects in view which will appear as the description proceeds, the invention consists in the novel features hereinafter described in detail, illustrated in the accompanying drawing and more particularly pointed out in the appended claims.

In the drawing:

Fig. 1 is a side elevation of my improved anti-skid device shown applied to a shoe.

Fig. 2 is a bottom plan view of the same.

Fig. 3 is a transverse vertical sectional view on the line 3—3 of Fig. 1.

Fig. 4 is an enlarged elevation of a detail.

Fig. 5 is a perspective view of the front portion of the device.

Fig. 6 is a similar view of the rear portion of the same.

Fig. 7 is a sectional view of a detail taken on the line 7—7 of Fig. 1.

My device consists of a toe section 8 and a heel section 9 adjustably and flexibly connected together by a spring link structure 10.

The toe section is preferably formed mainly of a single piece of wire, the medial portion of which is bent into T-shape as shown at 11 to provide a front arc-shaped portion 12 and oppositely extending arc-shaped wings 13. The ends of the wings are designed to rest against the outer surface of the side edges of the shoe sole 14, as best shown in Fig. 3, so as to maintain the toe piece 11 out of contact with the toe portion of the upper 15 of the shoe or rubber. Due to this feature the device will be prevented from damaging the toe portion of the shoe or rubber.

The legs of the T-shaped part 11 are secured together by a yoke or link 16 that is fixedly secured to the legs by welding or the like. The member 16, not only functions to prevent spreading of the legs, but as it lies immediately above the shoe sole, it will serve to hold the device in place. If the device is worn while sleighing, the yoke can be used as a spur to dig into the ice or snow and aid in guiding the sleigh.

Rearwardly diverging arms 17 are integral

with the legs of the T-shaped toe cap and terminate in upwardly extending posts 18 having eyes 19 at their upper ends. The arms are connected by front and rear cross bars 20 and 21 which may be formed of wire and welded to the arms. The ends of the cross bars are turned downwardly and are shaped to form front and rear barbs or spurs 22 and 23.

The rear section of the device is also preferably formed mainly of a single piece of wire, the medial portion of which is bent into T-shape to provide a post portion 24 and oppositely extending wings 26. The post and wings conform to the shape of the heel portion of a shoe or rubber and they serve to hold the heel portion of the device in position.

Forwardly diverging arms 27 are integral with the legs forming the post 24, and the front end portions of the arms form upwardly extending posts 28 terminating in eyes 29.

Front and rear cross bars 30 and 31 rigidly connect the arms 27 and they preferably terminate in spurs 32 and 33.

The adjustable means connecting the toe and heel sections of the device preferably consists of a pair of links 34 having eyes 35 at their forward ends which are hingedly connected to the eyes 19 of the toe section. These links extend freely through the eyes 29 of the heel section and their rear extremities are formed by eyes 36 which are of such size as to prevent them from passing through the eyes 29. Coil springs 37 have their ends connected to the eyes 29 and 35 to yieldingly hold the eyes 19 and 29 in relatively fixed relation to one another.

The connections 19, 35, allow the sections to be folded when the device is not in use and, of course, the springs 37 permit the device to be used with different sized shoes and also function to hold the device in place and on the shoe. The links 34 protect the springs when walking in brushy places.

While I have disclosed what I now believe to be a preferred embodiment of the invention in such manner that the same may be readily understood, I am aware that changes may be made in the details disclosed without departing from the spirit of the invention as expressed in the claims.

What I claim and desire to secure by Letters Patent is:

1. An anti-skid device for use with human footwear comprising a toe section and a heel section, means adjustably connecting the sections, the toe section including a substantially T-shaped toe protector having an arc-shaped central leg

and oppositely projecting arc-shaped wings, the extremities of which are adapted to rest against the edges of a shoe sole.

2. An anti-skid device for use with human footwear comprising a toe section and a heel section adjustably connected together, each of said sections having a substantially T-shaped portion forming an arc-shaped post and oppositely projecting arc-shaped wings.
3. An anti-skid device of the character described including a substantially T-shaped toe protector consisting of an arc-shaped central post and oppositely projecting arc-shaped wings, said post having a plurality of legs, and a link fixedly connected to said legs in close proximity to the lower ends of the latter and forming abutments at the front and rear of said legs.
4. An anti-skid device for human footwear comprising a toe section and a heel section adjustably connected together, each section being formed mainly of a single piece of wire, the medial portion of which is of T-shape, and the end portions of which form diverging arms terminating in upwardly extending posts.
5. An anti-skid device for human footwear comprising a toe section and a heel section, each section being formed mainly of a single piece of wire bent to provide a substantially T-shaped

portion to conform to a portion of a shoe, diverging arms to engage the bottom of a shoe, and upstanding posts, and means adjustably connecting the posts of the toe section to the posts of the heel section and supporting these sections. 5

6. An anti-skid device for human footwear comprising a toe section and a heel section, each section having a portion to underlie a shoe and eyes positioned above said portions, rigid links pivotally connected with the eyes of one section and extending loosely through the eyes of the other section, and springs surrounding the links and operatively connected to the eyes for drawing the sections toward one another. 10

7. An anti-skid device for human footwear comprising a toe section and a heel section adjustably connected together, one of said sections comprising a single piece of wire bent to form a T-shape part conforming to a portion of a shoe upper, the wire also forming diverging arms which are integral 20 with the T-shaped portion and are adapted to engage the bottom of a shoe, the wire also forming posts which are integral with the end portions of the arms, cross bars rigidly connecting the arms and adapted to engage the bottom of the 25 shoe, and spurs extending downwardly from the cross bars.

WILLIAM A. WALTHERS.
